[57] CLAIM

The ornamental design for a bag holder, as shown and described.

DESCRIPTION

FIG. 1 is a perspective view of the bag holder showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof, the opposite side being a mirror image thereof;

FIG. 7 is a perspective view of a first modification of the bag holder showing our new design;

FIG. 8 is a top plan view thereof, the bottom plan view being a mirror image thereof;

FIG. 9 is a front elevational view thereof;

FIG. 10 is a rear elevational view thereof;

FIG. 11 is a side elevational view thereof, the opposite side being a mirror image thereof;

FIG. 12 is an enlarged sectional view taken along the line 13—13 of FIG. 11;

FIG. 14 is a perspective view of a second modification of the bag holder showing our new design;

FIG. 15 is a top plan view thereof, the bottom plan view being a mirror image thereof;

FIG. 16 is a front elevational view of FIG. 14;

FIG. 17 is a rear elevational view of FIG. 14;

FIG. 18 is a side elevational view of the left side of FIG. 14; and,

FIG. 19 is a right side elevational view of FIG. 14.
